UNITED STATES PATENT OFFICE

96,674

DESIGN FOR A FECAL RECEPTACLE

Bernice F. Kapp, San Mateo, and John B. Craft,
San Francisco, Calif.

Application May 17, 1935, Serial No. 56,891

Term of patent 14 years

To all whom it may concern:

Be it known that we, Bernice F. Kapp and John B. Craft, citizens of the United States, residing at San Mateo, in the county of San Mateo, State of California, and San Francisco, in the county of San Francisco, State of California, respectively, have invented a certain new, original, and ornamental Design for a Fecal Receptacle, of which the following is a specification, reference being had to the accompanying drawing.

Figure 1 is a top plan view of a fecal receptacle embodying our design.

Figure 2 is a side elevation of a fecal receptacle embodying our design.

Figure 3 is a end elevation.

We claim:

The ornamental design for a fecal receptacle, as shown.

BERNICE F. KAPP.
JOHN B. CRAFT.
